UNITED STATES PATENT OFFICE.

HENRY E. NIESE AND GEORGE DINKEL, OF JERSEY CITY, NEW JERSEY,
ASSIGNORS TO THE F. O. MATTHIESSEN & WIECHERS SUGAR REFIN-
ING COMPANY, OF SAME PLACE.

PROCESS OF COOLING AND DRYING SUGAR.

SPECIFICATION forming part of Letters Patent No. 296,042, dated April 1, 1884.

Application filed November 6, 1883. (No model.)

To all whom it may concern:

Be it known that we, HENRY E. NIESE and GEORGE DINKEL, of Jersey City, New Jersey, have invented a Process of Cooling and Drying Sugar, of which the following is a specification.

As soft sugar, when discharged from the centrifugal machine in which it is drained, is frequently warm, it is desirable to cool it before packing it, and this has been done by causing it to fall upon a revolving scattering-wheel, by which the sugar was scattered, and in connection with which a cooling effect was produced by a current of air established by the rotation of the wheel or otherwise, and directed against the scattered sugar.

It is the object of our invention to more effectually separate the particles of sugar from each other, and to more thoroughly cool and dry them. To this end we subject the sugar to a process analogous to atomization by directing upon a column of falling sugar a powerful blast of air drawn from a comparatively cool source, whereby the particles of sugar are violently separated from each other and projected in a prescribed direction and cooled and dried. This operation may, if necessary, be repeated, if the sugar operated upon is either unusually warm or excessively moist.

The accompanying drawing, representing apparatus of simple character containing the features essential to the employment of our process, is as follows:

The figure is a vertical section representing portions of several floors of a building, showing the atomizer and part of a vertical pipe or chute for conducting sugar to the atomizer, also showing a bin for receiving the atomized sugar, provided with an outlet at the bottom, through which the sugar may fall to a lower floor through a pipe or chute, which may also be provided with an atomizer for repeating the atomizing and cooling operation, if necessary.

In practicing our process the sugar, after being drained in the centrifugal machine, is conducted to the vertical spout or pipe A, down which it falls by its own gravity into

the horizontal bend a at the lower end of the pipe A, the mouth a' of which constitutes the 50 discharge-opening out of which the sugar is violently driven by a strong blast of air forced through the air-pipe B by the blower B', and directed into the bend a by the nozzle b.

If the atmosphere of the room in which the 55 operation is performed is too high, the blower B' may be provided with a supply-pipe, B², leading from another room or chamber, the air of which is of the desired temperature.

It is desirable that the blast of air directed 60 into the bend a shall have great force, and we have found that with a fourteen-inch nozzle the necessary force can be imparted by a thirty-six-inch rotary fan-blower of the well-known Sturtevant type, revolving at the rate of six- 65 teen hundred revolutions per minute. By the action of the strong blast of air upon the sugar which falls into the bend a, the sugar is driven out of the mouth a', and the particles of sugar are thoroughly separated from each 70 other, and are projected, respectively, along the paths indicated by the diverging dotted lines C.

It will of course be understood that an inclined chute may be substituted for the vertical pipe A, and that the nozzle b may be inserted into the lower end of the chute, which may be bent horizontally or otherwise.

The air-blast nozzle a and means for directing the sugar downward to a point in front of 80 the nozzle a constitute what, for convenience, we call our "atomizer." The sugar, having been projected from the atomizer, falls by its own gravity into the collecting-bin D, the bottom d of which is of the usual inverted pyramidal form, inclined toward the outlet d', through which the sugar is discharged from the collecting-bin. If the sugar operated upon is excessively warm or moist, the atomizing, cooling, and drying operation may be repeated. 85 For convenience of repeating the operation, we arrange a second atomizer on the floor beneath the collecting-bin D, so that the sugar discharged through the outlet d' will fall into the chute E and be conducted to the horizontal bend e, in which is inserted the nozzle f

of another air-blast pipe, F, connected with the blower F'. From the second atomizer the sugar falls into the bin G, the bottom of which is inclined toward the outlet g, through which 5 the sugar is discharged from the bin G into the packing-room H. By this mode of treatment the particles of sugar are thoroughly cooled and dried, and the sugar may be at once packed away in barrels without the liability 10 of falling off in color which exists when the sugar is packed in barrels while warm.

It will be seen that the powerful blast of air which we employ performs the mechanical function of scattering the sugar, and so separates the particles of sugar from each other as 15 to fully expose them to direct contact with the air, thus cooling them by convection, and also evaporating the moisture from them.

We claim as our invention—

The process of cooling and drying soft sugar herein described, which consists in so guiding a moving mass of such sugar as to direct it into or near the mouth of a nozzle, from which issues a strong blast of suitably cool air, which performs the mechanical function of separating the particles of sugar from each other and scattering them, and thus fully exposing them to direct contact with the cool air, whereby such air carries off their heat and absorbs the moisture from them, and thus cools and dries 20 them. 25 30

HENRY E. NIESE.
GEORGE DINKEL.
